UNITED STATES PATENT OFFICE

JOHN W. SCHAFFNER, OF OAK PARK, ILLINOIS

BELT CONSTRUCTION

Application filed October 15, 1928. Serial No. 312,696.

My invention relates to improvements in belt constructions for conveying and elevating uses, the carrying face of which has high tractive and wear-resisting properties, and it 5 consists in the combinations, constructions, and arrangements herein described and claimed.

An object of my invention is to provide a belt construction which is provided with a 10 novel means which may be readily secured to the outer surface thereof for relieving the body of the belt from wear thereupon when used for conveying purposes.

A further object of my invention is to provide 15 a belt construction of the type described wherein the novel means for creating traction upon the outer surface as when conveying various objects is positive in its use and will retain the objects, even though at a relatively 20 steep incline.

A further object of my invention is to provide a belt construction of the type described in which the tractive and wear-resisting properties may be readily resurfaced, thereby 25 increasing the life of the belt.

A further object of my invention is to provide a belt construction of the type described in which the belt may be readily used for a positive driving connection if so desired.

30 Other objects and advantages will appear in the following specification, and the novel features of the invention will be particularly pointed out in the appended claims.

My invention is illustrated in the accompanying drawings, forming part of this application, in which—

Figure 1 is a perspective fragmentary view of the belt,

Figure 2 is a section substantially along the 40 line 2—2 of Figure 1,

Figure 3 is an enlarged section substantially along the line 3—3 of Figure 1, and

Figure 4 is a diagrammatic illustration of the belt used for conveying.

45 In carrying out my invention, I provide a belt having a body portion 1 which may be formed of any desired material, such as rubber, leather, canvas, or the like. A plurality of strips 2 is secured as spaced-apart positions 50 to the body portion 1 of the belt by any suit-

able means, such as stitching. The strips 2 may be formed of any suitable material, preferably that which is woven. The free edges of the strips 2 are combed out so as to provide a multiplicity of retaining ends or members 3. In this manner, a rough or uneven edge is provided for each side of each of the strips 2. A coating is then disposed upon the retaining members or ends 3 so as to form a cover 4 which is high in tractive and wear-resisting properties. The strips 2 are impregnated with any one of many materials high in tractive and wear-resisting properties; as, for example, synthetic gums, vegetable drying oils, mineral oils, and resinate dryers. The 55 frayed ends provide an irregular surface having unusually effective tractive properties. Since the edges are frayed, it will be noted that when the strips are impregnated, a heavy and irregular coating of the impregnated material will accumulate or adhere to the frayed ends. In view of the fact that the loose ends are frayed and more or less irregular in their arrangement, a peculiar edge is formed upon the strips, which, in connection with the strips proper, provide an effective construction. In the first place, the strips protect the main body portion of the belt; secondly, the strips provide means having effective tractive and wear-resisting properties; thirdly, the construction is such that when the strips become worn, they may be easily and quickly removed for permitting replacement. These covers cause the ends 3 to extend outwardly from the body portion 1 of the belt, thus causing 60 friction portions for a purpose hereinafter 65 described.

Let us assume that the belt is used for conveying various objects as illustrated in Figure 4. The objects, as indicated at 5, when disposed upon the belt will rest upon the strips 2 and upon the retaining members which include the ends 3 and the covers 4. The covers 4 being of high tractive and wear-resisting properties will hold the objects as 70 they are carried upon the belt. With this construction, the objects can be carried at a relatively steep incline without causing the objects to slide upon the belt.

When the covers 4 become worn after long 75 80 85 90 95 100

use, the ends 3 may be provided with new covers if so desired. Furthermore, new strips 2 may be provided by either first removing the old strips and then securing the new strips thereto, or by securing the new strips in place without removing the old strips. In this manner, the belt may be put to hard use and yet be relieved of the wear by the aid of the strips which have their two-fold purpose; i. e., relieving the body portion of the belt from the wear of the objects which are conveyed thereupon and providing tractive portions by means of which objects may be conveyed up a relatively steep incline.

It may be observed that the belt as shown with the strips and their retaining members may be used efficiently in the reverse position for providing a positive driving connection between two pulleys.

I claim:

1. A belt construction comprising a body portion having a plurality of longitudinally disposed strips secured thereto, said strips being provided with frayed edges, the strips and said frayed edges being impregnated and coated with a material having tractive properties.

2. A belt construction comprising a body portion having a strip secured thereto and arranged in longitudinal alignment therewith, said strip being provided with frayed edges and impregnated with a material having tractive properties.

3. A belt construction comprising a body portion having a plurality of strips arranged in longitudinally extending alignment with the longitudinal axis of the body portion of the belt and secured thereto, the edges of said strips being frayed and projecting laterally from said strips.

Signed at Chicago, in the county of Cook and State of Illinois, this 9th day of October, A. D. 1928.

JOHN W. SCHAFFNER.
